US0D1038750S

(12) **United States Design Patent** (10) **Patent No.:** **US D1,038,750 S**
(45) **Date of Patent:** **** Aug. 13, 2024**

(54) **PRODUCE CONTAINER**

(71) Applicant: **NS Brands, Ltd.**, San Antonio, TX (US)

(72) Inventors: **Lauren Danielle Behl**, San Antonio, TX (US); **Andrés Londoño Orrego**, Jalisco (MX)

(73) Assignee: **NS Brands, Ltd.**, San Antonio, TX (US)

(**) Term: **15 Years**

(21) Appl. No.: **29/803,906**

(22) Filed: **Aug. 17, 2021**

(51) **LOC (14) Cl.** **09-03**

(52) **U.S. Cl.**

USPC **D9/430**
